SMOKING PIPE

John M. Boscardin, Hartford, Conn.

Application July 15, 1938, Serial No. 219,506

7 Claims. (Cl. 131—224)

My invention relates to smoking pipes.

It has among its objects to provide an improved pipe wherein, while the pipe is free from obstruction during loading and lights more easily and burns more uniformly, it is made possible to provide a cool smoke and to collect the nicotine and minimize the discharge of objectionable matter into the smoker's mouth. A further object of my invention is to provide an improved appliance adapted to use in connection with any standard form of pipe while performing the above functions, and further adapted to be readily and quickly applied to or removed from a pipe while facilitating the emptying of the latter, and also being adapted to be readily cleansed and to be inexpensively manufactured. These and other objects and advantages of my improved construction will, however, hereinafter more fully appear.

In the accompanying drawing I have shown for purposes of illustration three embodiments which my invention may assume in practice.

In the drawing—

Figure 1 is a central vertical section through a pipe equipped with one form of my improvement;

Fig. 2 is an enlarged side elevation of the appliance shown in Figure 1, removed from the pipe;

Fig. 3 is a like view of a modified form of appliance, and

Fig. 4 is a like view of a further modified form of the same.

Referring first to the illustrative form of the construction shown in Figures 1 and 2, it will be observed that I have shown a pipe 1 of a standard construction having a usual bowl 2 and air passage 3 in the stem 4 and also provided with my improved appliance, generally indicated at 5, in the bottom of the bowl 2 and between the latter and the air passage 3.

My improved appliance is of generally ball, or spherical, form and preferably is made of light material, such, for example, as aluminum and in all the forms shown has a rigid outer crust. Further, in the form shown in Figures 1 and 2, it will be noted that its outer crust is provided with a series of deep cuts 6 disposed in spaced relation around the ball. More particularly, it will be observed that in these figures, I have shown a round ball provided with a series of such spaced cuts arranged in parallel spaced relation around the ball and cooperating series of cuts 6' and 6'' disposed at right angles to and intersecting the cuts 6. Obviously, however, the cuts may be disposed in various arrangements while still con-

tinuing to provide spaced passages inside the outer surface of the ball. Preferably, however, these cuts are so disposed as to be distributed uniformly over the entire peripheral surface of the ball. Further, while in this form of my invention I preferably utilize a solid ball, I may use a hollow ball, if desired. Further, while aluminum is preferred on account of its lightness and affinity for heat and its known adaptability to be quickly and completely cleansed, it will be understood that other metals, materials or compositions may be used, if desired, as, for example, terra cotta.

As a result of my improvement, the cuts or grooves 6 cooperate to provide a series of passages so disposed that however the ball 5 is dropped into a pipe bowl, it will locate itself at the bottom of the bowl and over the intake of the air passage 3. Thus, while in no way obstructing loading, it always functions in any position to provide a series of air passages leading around the ball to the air passage 3 in the stem. Also, due to the upward projection of the upper surface of the ball, the tobacco is not packed tight over the sides of the ball, so that lighting is expedited. Thus, my improved construction is such as to make burning during both lighting and smoking, markedly more uniform. Moreover, the smoke passing out through the passage 3 is cooled due to the heat absorptive qualities of the ball, while nicotine or other substances entrained with the smoke, are collected upon the walls of the cuts or grooves in such manner as to minimize the amount of the same transmitted to the mouth and lungs of the smoker.

In the use of my improvement, it will be evident that my improved ball will tend to locate itself in the correct position when simply dropped into the bowl of a pipe. Further, when it is desired to remove the ball, all that it is necessary to do is to invert the pipe. The presence of the ball further tends to eliminate the formation of the usual wet caking over the inlet of the air passage 3, while when the ball is removed by inverting the pipe, or knocking out the same in a usual manner, the ball will carry with it any remaining unburnt tobacco, or ashes. Obviously, when removed, the ball may also be readily cleansed for further use in any suitable manner, as, for example, by washing it under running hot water. Here also it will be understood that while I have shown only a ball of a single size, I contemplate the use of balls of such different sizes as to be adapted to the particular size of pipe, as, for example, small, medium and large balls adapted to

- use in small, medium and large pipes. It will also be evident that, if desired, the ball may be of such size as when pressed downward in the bottom of the bowl, to frictionally engage the 5 wall of the bowl and remain therein when the pipe is emptied, while still being readily removable when the pipe is tapped more briskly during emptying. In all sizes, it will further be noted that any tendency to draw tobacco into the 10 stem, in such manner as to plug the same, is also effectively minimized. These and other advantages of my improved construction will, however, be clearly apparent to those skilled in the art.
- 15 In Figure 3, I have illustrated a modified form of ball, generally indicated at 7, which may be used if desired. This ball, however, is provided with a rough surface, indicated at 8, and is also preferably made of aluminum. Obviously, while 20 in this form of my invention, the passage means are not as definitely defined as in Figures 1 and 2, such passage means will be provided by the rough surface. The same applies to the modification shown in Figure 4 wherein a hollow aluminum ball 9 is provided having an outer rigid shell provided with perforations 10 distributed uniformly over the same and having communication provided between one another and the bowl 2 and air passage 3 by a hollow center or chamber 11.
- 25 30 While not preferred for various reasons, including the fact that they are not so readily cleaned as the construction shown in Figures 1 and 2, it will be evident that these modified constructions will function generally similarly in view of their ball form and the uniform distribution of the air passage means provided by the rough surface 8 and perforations 10.

As a result of my improved construction, it will be observed that in all forms a ball is provided 40 which cannot be distorted in use, the same instead retaining its ball form due to the rigid surface thereof. Moreover, making the ball rigid, whether the ball is solid or hollow, enables it to be readily formed of aluminum, terra cotta, or 45 other like material having an affinity for heat, in such manner as to provide a cool smoke, while having the strength inherent in a ball. At the same time that such an outer surface or shell is provided, and the above advantages are obtained, the passage means are so formed therein and distributed thereover as not only to permit the periphery of the ball to be readily cleansed, but also to permit these passage means to be so distributed over the outer shell or surface of the ball as to enable the latter to be dropped in any position into the pipe and function equally well in all 55 positions.

While I have in this application specifically described three forms which my invention may 60 assume in practice, it will be understood that these forms of the same are shown for illustrative purposes, and that the invention may be modified and embodied in various other forms without departing from its spirit or the scope of the appended claims.

65 What I claim as new and desire to secure by Letters Patent is:

1. A smoker's accessory for insertion in the bot-

tom of a pipe bowl, comprising a substantially spherical member having a rigid outer crust and passage forming means therein forming passages of predetermined size and direction, some of said passages being located transversely to others so 5 that in whatever position the member is placed within the bowl there will be communication for smoke between the bowl and the pipe stem.

2. A smoker's accessory for insertion in the bottom of a pipe bowl, comprising a substantially 10 spherical member having a rigid outer crust and passage forming means therein forming passages of predetermined size and direction, certain of said passages being located transversely to others so that in every position of said member within 15 the pipe bowl like communication will be provided for smoke between the bowl and stem.

3. A smoker's accessory for insertion in the bottom of a pipe bowl, comprising a substantially 20 spherical member having a rigid outer crust and passage forming means therein forming passages of predetermined size and direction, some of which are located transversely to others, said member providing in every position thereof in the bowl an arcuate supporting surface for the tobacco therein while also providing communication for smoke through said means from the bowl 25 to the pipe stem.

4. A smoker's accessory for insertion in the bottom of a pipe bowl, comprising a substantially 30 spherical member having a rigid surface and having means therein forming substantially uniformly distributed passages in the exterior surface, some of the passages being transverse to other passages so that in whatever position the 35 member is placed within the bowl there will be free communication for smoke from the bowl to the pipe stem.

5. A smoker's accessory for insertion in the bottom of a pipe bowl, comprising a substantially 40 spherical member having a rigid outer crust and grooves in the surface thereof forming smoke conducting passages of predetermined size and direction, certain of said passages being located 45 transversely to others so that in all positions of said member in the bowl the portion of said member which is in contact with the tobacco provides communication through said grooves from the bowl to the stem.

6. A smoker's accessory for insertion in the bottom of a pipe bowl, comprising a substantially 50 spherical member having a rigid outer crust and a plurality of surface projections thereon adapted to engage the pipe bowl and space the surface of said member therefrom to provide smoke conducting passages between the bowl and stem in 55 any position of insertion of said member in the bowl.

7. A smoker's accessory for insertion in the bottom of a pipe bowl comprising a substantially 60 spherical member having a rigid outer shell and passage forming means therein providing communication between a pipe bowl and stem, said passage forming means comprising perforations in said shell distributed over the surface thereof and a chamber within said shell through which 65 said perforations communicate.

JOHN M. BOSCARDIN.
